UNITED STATES PATENT OFFICE.

JULIUS LIBROWICZ, OF NEW YORK, N. Y.

DESIGN FOR A BOTTLE.

SPECIFICATION forming part of Design No. 22,138, dated January 17, 1893.

Application filed November 3, 1892. Serial No. 450,902. Term of patent 7 years.

To all whom it may concern:

Be it known that I, JULIUS LIBROWICZ, a citizen of the United States, residing at New York, county of New York and State of New York, have invented and produced a new and original Design for Bottles, of which the following is a specification.

Reference is to be had to the accompanying drawings, forming part of my specification, in which—

Figure 1 is a perspective side elevation, showing the obverse of the bottle in full. Fig. 2, a like elevation, showing the reverse in full; and Fig. 3, a sectional elevation taken approximately on the line xx , Fig. 2.

In general outline my bottle shows an architectural structure, the lower portion of which resembles a temple of the Grecian order, and which is approximately rectangular in shape, from which rises a cupola, cylindrical in shape, surmounted by a cap of trunco-pyramidal form, having a cylindrical extension thereon. The base or temple portion is shown at 1; the cupola at 2; the cap at 3, and the extension at 4. The obverse side of the temple is shown at 5 (Fig. 1), and the reverse at 6 (Fig. 2.) The obverse face of the temple has the projecting steps 7, surmounted by a pillared portal 8 and a cornice 9 of flutings 9. The steps, portal and fluting do not occupy the entire side, the cornice being continued (though set back) around the four sides of the temple, as at 10, as are two other flutings 11, 12, one at the base of the temple, the other a little above that, and between these flutings lies a panel 25, which extends entirely around the temple, except where intercepted by the steps 7. On the obverse the space between the cornice 10 and fluting 11, except that occupied by the pillared portal, is flat, as at 13, and this figure represents a flat space on all sides of the tem-

ple. A panel 14 lies above the cornices 9, 10, and extends entirely around the four sides of the temple; and above this lies the superior 45 cornice 15 which extends in like manner around the temple. On the two rimmed sides of the temple, to wit: 16, 17, a balustrade 18 lies above the cornice 15, and which has at the corners or angles of the temple upright 50 blocks 19; and between these blocks on the obverse and reverse sides lies the ornamented partial portico 20, the whole being covered (in part) by a slanting roof 21. On the reverse side a bay 22, segmental in form is produced, having the pillars 23, and which is provided with the convex roof 24 merging into the panel 14. The cornice and flutings 10, 11, 12 extend around the bay, as does the panel 25. The sides, other than the obverse 60 and reverse, are provided with pillars 40. Surmounting the temple portion 1 is the cupola portion 2, which is mainly divided into three cylindrical portions 26, 27, 28, having interposed beads 29, 30. The sections 27, 28 65 are ornamented by the pillars 31 and blocks 32, respectively, the blocks having disks 33. The section 26, which is larger than the other two, is castellated, as at 34. The beading 29 is plain, while the beading 30 has a castellated ornamentation 35. The cap 3, which is trunco-pyramidal in sectional contour, is provided with a series of concentric flutings 36 which end at the base of the extension 4, which is cylindrical in shape. 75

I claim:

The design for a bottle, substantially as shown and described.

Signed at the city, county, and State of New York this 2d day of November, 1892.

JULIUS LIBROWICZ.
